ATTORNEY

UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

AUTOMATICALLY-THREADING SHUTTLE FOR LOOMS.

Application filed October 26, 1926. Serial No. 144,213.

This invention relates to an automatically threading shuttle for looms wherein the shuttle becomes threaded during its "picking" movements.

5 The present invention is a further development of the automatically threading shuttles shown and described in the Stimpson Patents, Nos. 1,483,492, February 12, 1924, and 1,538,224, May 19, 1925, in which the 10 threading end of the shuttle is provided with a thread casting device for casting the thread out of the longitudinally extending thread passage on the occurrence of a loop or overthrow as the shuttle comes to rest in 15 the replenishing box, and while the advantages of the invention as hereinafter described are particularly manifested in the automatically threading shuttles to which reference has been made, some of its features 20 may be utilized in other characters of shuttles.

During the weaving operation as the shuttle is "picked" the filling thread as it is withdrawn from the filling carrier or bobbin swirls or takes a generally circular path about the end of the filling carrier or bobbin, and for the best weaving results such swirling or circular path of the filling thread should be about an axis central of 25 the filling carrier or bobbin, otherwise, the thread will draw at times over the end portion of the filling carrier and have imparted thereto a retarding action different from the retarding action at the opposite side or 30 other portions of the filling carrier or bobbin. One of the important features of the present invention consists in means for confining the swirling action of the thread about a central axis in prolongation of the 35 central longitudinal axis of the filling carrier or bobbin, whereby the tensioning effect 40 on the thread remains substantially uniform.

In automatically threading shuttles of the 45 general type shown and described in the Stimpson patents, the longitudinally extending thread passage is provided with a thread casting device in the general form of a scroll extending from a point adjacent 50 the bobbin chamber towards the forward end of the thread passage, and on shuttle threading or the occurrence of an overthrow the thread at times is liable to be caught in 55 the recess between the side wall of the thread passage and the adjacent portion of

the scroll, and another important feature of the present invention therefore consists in means for obviating this difficulty and the objections incident thereto.

The invention and novel features thereof 60 and new combination of parts will best be made clear from the following description and the accompanying drawings of one good form thereof.

In the drawings:

Fig. 1 is a perspective view of the threading end of a shuttle containing the present invention;

Fig. 2 is an enlarged perspective view of the threading block or eye detached;

Fig. 3 is an end view of the threading block looking from the bobbin chamber;

Fig. 4 is a plan view of the threading block; and

Fig. 5 is a plan view showing the path of 75 the thread as it is withdrawn from a shuttle containing the present invention.

The shuttle 1 is provided with a bobbin chamber 2 and forward of the bobbin chamber the shuttle is provided with a 80 longitudinally extending thread passage through which the thread is drawn through the side delivery eye 6. In the present instance of the invention the shuttle is provided at its forward or threading end portion with a threading block chamber 3 in which is mounted the threading block 4 which may be formed as the similar threading blocks in either of the Stimpson patents hereinbefore mentioned. The threading 85 block 4 has a longitudinally extending thread passage 5 which communicates with the side delivery eye 6, and leading from the longitudinally extending thread passage the wood of the shuttle is recessed or cut away as at 7. Extending in a lateral direction relative to the longitudinally extending thread passage is the thread director 8, the end portion of which is provided with a thread catch 9 which extends closely to the 90 adjacent wall of the thread leading recess 7.

In the present instance the scroll 10 has the downwardly extending portion 11 which passes through a slot 12 in the threading block and has its foot portion 13 turned laterally in the recess at the lower face of the block, the result being that the scroll 10 extends upwardly, laterally and forwardly in the longitudinal thread passage from a point adjacent the bobbin chamber, the end 105 110

portion 14 of the scroll preferably being adjacent to the transversely extending bridge 15 over which the thread passes on its way to the side delivery eye.

From the construction thus far described it will be noted that the filling thread *a* as it is withdrawn from the filling carrier or bobbin 16 in the bobbin chamber will be laid longitudinally of the thread passage over the bridge 15 on its way to the side delivery eye, and owing to the tension of the thread as it is laid in the shed, the filling thread *a* will naturally take a position over the bridge at the side adjacent to the side delivery eye upon its way thereto, with the result that the filling thread *a* will swirl or take its curvilinear path about an axis which is not coincident with the central longitudinal axis of the filling carrier or bobbin. This fact may not be objectionable in the use of certain characters or kinds of filling thread, and a shuttle provided with the threading block construction hereinbefore described has proved to be efficient and practical in operation.

In weaving with certain characters of yarn, however, it is desirable that the yarn tension be maintained uniform at all times, and to effect such uniformity of tension the swirling action of the thread, in the present invention, is confined about an axis extending longitudinally and centrally of the filling carrier or bobbin.

In accordance with the present invention, a thread guiding rib is located in the thread passage between a part of the scroll and the bridge, and its thread guiding edge is in substantial alignment with the central longitudinal axis of the filling carrier or bobbin, with the result that as the thread is withdrawn from the shuttle during weaving, it will bear upon the guiding edge of the rib and its swirling action will be confined to an axis in prolongation of the central longitudinal axis of the filling carrier or bobbin.

The threading block 4 has extending therefrom the thread guiding rib 17 which may be appropriately cast with the threading block or formed otherwise to provide a thread guiding edge portion in substantial alignment with the longitudinal axis of the filling carrier or bobbin. As shown, the rib 17 projects from one side wall of the threading block and extends between the front guiding wall 18 of the scroll inwardly of the scroll at a point between such guiding edge and the bridge 15, with the result that the thread as it is withdrawn from the filling carrier or bobbin will take a swirling path in prolongation of the central longitudinal axis of the filling carrier or bobbin.

The effect of this is indicated in Fig. 5 wherein the filling thread *a* leads from the filling carrier or bobbin 16 over the thread guiding portion of the rib 17, and since the thread guiding portion of the rib 17 is in

alignment with the central longitudinal axis *b* of the filling carrier or bobbin, the swirling action of the thread will be confined to a path central of the filling carrier or bobbin and be directed to the bridge 15 on its way to the side delivery eye with unvarying tension.

The rib 17 extends from the top portion of the threading block in a downwardly and inwardly curved direction, as indicated at 19, to a point substantially in the longitudinal axis of the scroll, and joins the lower wall 20 of the threading block. The downwardly and inwardly inclined portion 19 of the rib 17 is utilized to prevent the thread being caught in the recess 21 between the heel portion of the scroll and the adjacent side wall of the thread passage, as indicated in Fig. 3.

Should a loop or overthrow occur during weaving, or should the thread engage the top of the scroll on the first pick of the shuttle following replenishment, the upper inclined portion 19 of the thread guiding rib will prevent the thread from being caught between the scroll and the adjacent side wall of the longitudinally extending thread passage.

For the best results, the thread guiding rib 17 is located between the guiding edge 18 of the scroll and the bridge 15, but the invention is not necessarily restricted in this respect, the essentials being that the thread guiding edge of the rib be extended substantially to the longitudinal axis of the scroll between the bobbin chamber and the bridge over which the thread passes to the side delivery eye, whereby the lateral pull on the thread through the side delivery eye will not disturb the axis of the swirling action of the thread during weaving.

What is claimed is:

1. An automatically threading loom shuttle having a bobbin chamber, a longitudinally extending thread passage and a side delivery eye, a scroll extending forwardly in the longitudinal thread passage from a point adjacent the bobbin chamber, and a guide rib extending into the scroll from the side wall of the thread passage and between the ends thereof to guide the thread from the scroll to the side delivery eye.

2. An automatically threading loom shuttle having a bobbin chamber, a threading block having a longitudinally extending thread passage, a bridge at the forward end of the thread passage, a scroll extending longitudinally of the thread passage from a point adjacent the bobbin chamber towards the bridge, and a thread guide extending transversely of the thread passage back of the bridge to guide the thread on its way from the bobbin chamber to the side delivery eye.

3. An automatically threading loom shut-

tle having a bobbin chamber, a threading block having a longitudinally extending thread passage, a bridge at the forward end of the thread passage, a scroll extending longitudinally of the thread passage from a point adjacent the bobbin chamber towards the bridge, and a thread guide extending transversely of the scroll at a point back of the bridge to guide the thread in the thread passage as it is withdrawn from the filling carrier.

4. An automatically threading loom shuttle having a bobbin chamber, a threading block having a longitudinally extending thread passage and a bridge at the forward end of the passage, a scroll extending from a point adjacent the bobbin chamber towards the bridge, and a thread guide in the thread passage back of the bridge for directing the thread about an axis substantially in prolongation of the longitudinal axis of the bobbin as it is withdrawn therefrom.

5. An automatically threading loom shuttle having a bobbin chamber, a threading block having a longitudinally extending thread passage and a bridge at the forward end of the passage, a scroll extending from a point adjacent the bobbin chamber towards the bridge, and a thread guide in the thread passage back of the bridge and extending into the scroll for directing the swirling thread about an axis substantially

central of the longitudinal axis of the filling carrier as it is withdrawn therefrom. 35

6. An automatically threading loom shuttle having a side delivery eye and a threading block provided with a longitudinally extending thread passage, a scroll in the thread passage, and a thread guide extending into a convolution of the scroll to direct the swirling thread about the longitudinal axis of the filling carrier as the thread is withdrawn therefrom. 40

7. An automatically threading loom shuttle having a side delivery eye and a threading block provided with a longitudinally extending thread passage, a scroll in the thread passage, a bridge forward of the scroll, and a thread guide between a convolution of the scroll and the bridge to direct the path of the thread as it is withdrawn from the filling carrier. 45

8. An automatically threading loom shuttle having a longitudinally extending thread passage and side delivery eye, a scroll in the thread passage and a guide rib extending downwardly and transversely from the top of the thread passage to direct the thread and guard it from catching between the scroll and side wall of the thread passage. 50

In testimony whereof, I have signed my name to this specification.

HARRY A. DAVIS.
